United States Patent Office

Des. 205,255
Patented July 12, 1966

205,255

SAILBOAT

John Henry Shelley, Chez Nous, Msida, Malta

Filed Aug. 20, 1965, Ser. No. 86,659

Term of patent 14 years

(Cl. D71—1)

FIG. 1.

FIG. 2.

FIG. 4.

FIG. 5.

FIG. 3.

FIGURE 1 is a top plan view of the present novel design for a sailboat;

FIGURE 2 is a bottom plan view of the same;

FIGURE 3 is a side elevational view of the same;

FIGURE 4 is a front end view of the same; and

FIGURE 5 is a back end view of the design.

The dominant features of my design reside in the portions shown in full lines, with the broken lines portions being omitted from FIGURES 1, 2, 4 and 5 for convenience of illustration.

I claim:

The ornamental design for a sailboat, as shown and described.
